UNITED STATES PATENT OFFICE.

HELGO WIGGO JESPERSEN, OF WESTERN SPRINGS, ILLINOIS, ASSIGNOR TO WESTERN ELECTRIC COMPANY, INCORPORATED, OF NEW YORK, N. Y., A CORPORATION OF NEW YORK.

MECHANISM FOR WORKING PULPOUS MATERIAL.

Application filed May 16, 1924, Serial No. 713,705. Renewed October 18, 1926.

This invention relates to improvements in mechanism for working pulpoous material, and more particularly to mechanism for forming such material to constitute a homogenous coating for cores in strand form such as wire and the like.

Mechanisms made in accordance with this invention are particularly well adapted for use in connection with the method and apparatus for coating cores disclosed in the co-pending application of H. G. Walker, Serial No. 621,242, filed February 26, 1923, but it is to be understood that the invention is not limited to such use, but only in so far as defined by the appended claims.

An object of the invention is to provide improved means for adjusting the forming member of a forming mechanism adapted to work pulpoous material into a homogenous coating for cores.

Another object of the invention is to provide improved means for regulating the force with which a forming member of a forming mechanism engages the pulpoous material on a core.

Another object of the invention is to provide a forming mechanism which will operate upon the pulpoous material so as to form it into a homogeneous and uniform coating.

A further object of the invention is to provide a forming mechanism which may be operated at high speed and will not strip the coating material from the core during the forming operation.

In one embodiment of the invention the forming mechanism comprises a rotatable head adapted to carry a plurality of forming members, the forming members being pivotally mounted in the head and disposed to engage the pulpoous material on a core being drawn through the head.

Each forming member comprises a blade provided with an apertured boss, whereby the blade is rigidly secured to a tubular shaft, which is in turn rotatably journaled in the head. A wire having the greater portion of its length disposed in the tubular shaft has one of its ends rigidly secured to the tubular shaft. Means is provided at the other end of the wire for twisting the wire to place it in torsion. The wire then tends to force its associated forming blade into pressing engagement with the pulpoous material on the core being drawn through the head.

The amount of torsion in

the wire is adjustable. A sleeve disposed in the head may be adjusted to space the forming blades a predetermined distance apart so that the forming members will work the pulpoous material into a uniform coating.

Other objects of the invention will become apparent as the detail description progresses, reference being had to the accompanying drawing, in which.

Fig. 1 is an elevation of a forming mechanism embodying the invention;

Fig. 2 is a section taken on lines 2-2 of Fig. 1;

Fig. 3 is an enlarged detailed view showing the mechanism for bringing one of the forming members into pressing engagement with the pulpoous material on the core;

Fig. 4 is an end elevation partly in section of the mechanism shown in Fig. 1,

Fig. 5 is a section taken on line 5-5 of Fig. 1;

Figs. 6 and 7 are enlarged sectional views illustrating the manner in which the pulpoous material is applied to the core before it is delivered to the forming mechanism; and

Figs. 8 and 9 are enlarged sectional views showing the forming of a pulp coating during the forming operation and after the completion of the forming operation respectively.

The forming mechanism shown in the accompanying drawing is especially adapted to operate in conjunction with apparatus shown in the aforementioned application of H. G. Walker, Serial No. 621,242, filed February 26, 1923, which apparatus is adapted to apply pulpoous material to a core and comprises a foraminous member and a plurality of felt-covered squeezing rolls. In the operation of this apparatus, the core is first brought into contact with pulpoous material deposited upon the foraminous member and then an additional amount of pulpoous material is deposited upon the core and the foraminous member. The pulp, so deposited, and the core are then brought into contact with one of the squeezing rolls which cooperates with the foraminous member to squeeze out the "free liquid", so to speak, in the pulp coating. The partially dried pulp adheres to the felt of the squeezing roll in the form of a ribbon with the core substantially centrally located therein as shown in Fig. 6 of the accompanying drawing, and the core with the pulp ribbon attached thereto passes around the roll

and between it and its cooperating roll, the contour imparted to the ribbon by the squeezing rolls being shown in Fig. 7.

The forming mechanism embodying the features of the present invention is designed to receive the core and its ribbon from the squeezing rolls and to wrap the projecting edges of the ribbon around the core and around each other until it conforms substantially to the shape of the core. The appearance of the coating after it is first acted upon by the forming mechanism is shown in Fig. 8, and the appearance thereof after the forming action is completed is shown in Fig. 9.

Referring to the drawing, the forming mechanism comprises a rotatable head 10 composed of a body portion 11 and an end plate 12. The head 10 has one of its ends threaded into one end of a sleeve 13, which is rotatably journaled in suitable bearings, one of which is shown at 14. A pulley (not shown) may be rigidly secured to the sleeve 13 and will provide means whereby the sleeve and head may be rotated at any desired speed. The head 10 and sleeve are adapted to accommodate a core 15 carrying a ribbon 16 of pulpous material. When the forming mechanism is in operation, the core 15 with its ribbon 16 is drawn through the forming mechanism by any suitable means (not shown), the core and ribbon entering the mechanism from the left, Fig. 1. The head 10 may be termed a "rotatable carrier" as it carries a plurality of forming members 18 adapted to engage the ribbon of pulpous material and to form it into a uniform coating for the core, the completed coating being shown in Fig. 9.

Each forming member 18 comprises a plate 19 adapted to engage the pulpous material 20 and provided with an apertured boss 21 whereby the plate is rigidly secured to one of a plurality of shafts 21 rotatably journaled in the head 10, a pin 22 being employed to secure the plate 19 to the tubular shaft 21. As best shown in Fig. 3, one end of each tubular shaft 21 is rotatably journaled in a recess 23 in the body portion 11 of the head 10, the end thrust of the shaft being received by a metallic ball 24 disposed in the recess. The other end of each shaft 21 is rotatably journaled in a dial member 25 which is in turn rotatably journaled in the end plate 12 of the head 10. Each tubular shaft 21 is provided with a torsion wire 26 which projects from one end of the tubular shaft. The inner end of the torsion wire is soldered to the tubular shaft as indicated at 27, the tubular shaft 21 being provided with a transverse hole 28 to receive the solder. The outer end of each torsion wire 26 is bent to lie in a slot 30 formed in the associated dial 25. This construction permits the torsion in the wire 26 to be adjusted as the dial 25 may be rotated to twist the wire in either direction, the slot 30 providing means whereby an edged tool may be em-

ployed to rotate the dial. Each dial 25 has a washer 31 rigidly secured to it, the washer being adapted to engage the inner face of the end plate 12 and to prevent longitudinal displacement of the dial relative to the end plate. Means is provided for locking each dial in any one of its adjusted positions. This means comprises a pin 33 loosely seated in a bore 34 formed in the end plate 12. The pin 33 is provided with an arcuate surface 35 adapted to frictionally engage the dial, a set screw 36 being provided to force the pin 33 into engagement with the dial.

A counterweight 38 is provided for each plate 19. The counterweight 38 is pivotally mounted on the associated tubular shaft 21 and may be secured in a plurality of adjustable positions with respect to the plate by means of a plurality of set screws 39 threaded into the counterweight and adapted to engage the tubular shaft. The counterweights 38 may be secured in positions wherein they balance the plates 19 during the operation of the forming mechanism, it being readily understood that during the operation of the forming mechanism, the plates 19 tend to draw away from the core 15 because of the centrifugal force generated by the plates when they are carried bodily around the core. This tendency of the plates to draw away from the core is overcome by the counterweights 38.

A sleeve 40 rotatably journaled in the head 10 and provided with triangular lugs 41 adapted to enter between the plate 18 may be brought into a plurality of adjustable positions with respect to the plates to space the plates from the core 15. The means for bringing the sleeve 40 into a plurality of adjustable positions with respect to the plates 19 comprises a pin 42 rotatably journaled in the head 10 and provided with a pin 43 adapted to engage a circumferential slot 44 formed in the sleeve 40. The pin 43 projects from one end of the pin 42 and is disposed eccentrically with respect to the axis of rotation thereof. It is obvious that if the pin 42 were angularly displaced, the pin 43 would displace the sleeve 40 toward or away from the plates 19 so that the triangular lugs 41 may gauge the positions of the plates 18 with respect to the core. It will be noted that the pin 42 is provided with a slot 45 adapted to receive a screw driver or the like, thus enabling the operator to rotate the pin to bring the sleeve 40 into an adjusted position. A set screw 46 threaded into the head 10 engages an annular groove 47 formed in the pin 42 and may be forced against the pin until the pin is locked against rotation. A pin 50 driven into the head 10 projects into a longitudinal slot 51 formed in the sleeve 40 and is adapted to prevent angular displacement of the sleeve relative to the head.

In the operation of the device the torsion of

the wire 26 is first adjusted by means of the dials 25 which are graduated for this purpose. The counterweights 38 are then adjusted to positions corresponding with the amount of torsion obtaining in the wires 21. The forming mechanism is then rotated and the core 15 with its ribbon 16 of pulpos material is drawn between the plates 19 which wrap the ribbon of pulpos material around the core until the pulpos material forms a uniform coating for the core.

What is claimed is:

1. In a mechanism for working pulpos material on a core, a forming member comprising a movable element, a straight wire

having one end secured to said element, and means for twisting the wire to cause it to force the movable element against said pulpos material.

2. In a mechanism for working pulpos material on a core, a forming member comprising a movable element, a straight wire having one end secured to the movable element, and means for rotating the other end of the wire to cause the wire to force the movable element against said pulpos material.

In witness whereof, I hereunto subscribe my name this 29th day of April A. D., 1924.

HELGO WIGGO JESPERSEN.
